UNITED STATES PATENT OFFICE.

LEWIS G. YOUNG, OF NEW YORK, N. Y.

AEROPLANE.

1,266,746.

Specification of Letters Patent. Patented May 21, 1918.

Application filed October 2, 1917. Serial No. 194,307.

To all whom it may concern:

Be it known that I, LEWIS G. YOUNG, a citizen of the United States, and a resident of the borough of Manhattan of the city of New York, in the State of New York, have invented certain new and useful Improvements in Aeroplanes, of which the following is a specification, reference being had to the accompanying drawing, forming a part hereof:

This invention relates particularly to the wing structure of aeroplanes and it has for its object to provide fittings which shall hold securely in place the wing struts, and afford suitable anchorage for the drift wires while dispensing with turnbuckles and leaving the adjusting nuts readily accessible, and shall reduce weight to a minimum. The invention will be more fully explained hereinafter with reference to the accompanying drawing in which it is illustrated and in which—

Figure 1 is a fragmentary view showing in elevation and partly in section a portion of a wing-spar, portions of an internal, tubular strut and adjacent drift wires, and an improved fitting.

Fig. 2 is a top view of the same with one of the drift wires removed.

Fig. 3 is a detail view showing the fitting in section on the plane indicated by the broken line 3—3 of Fig. 1.

A wing-spar, usually of wood, of one of the planes of an aeroplane, is shown at *a* in the drawing, with a portion *b* of a strut. It will be understood that as usual several such struts are interposed, as compression members, between the spars of a wing. Drift wires or guy wires or tension members *c* also extend as diagonals from one spar to another. The strut usually bears at each end against a bearing plate *d* which is interposed between the end of the strut and the spar. It is necessary to provide means to prevent the end of the strut from slipping to one side or another on the spar and it is also necessary to provide means, adjacent the end of the strut, for the anchorage of the drift wires or tension members *c*.

For this purpose there is provided, in accordance with the present invention, a strut fitting *e*, which is arched longitudinally, as clearly shown in Fig. 1, is made concavo-convex in cross section, as clearly shown in Fig. 3, and has at its ends flat feet to rest

against the spar and to receive the bolts *f* by which it is secured to the spar. It is provided centrally with an aperture *g* to receive, with a reasonably snug fit, the end of the strut *b*, and it is also slotted, as at *h*, to receive the ends of the eye-bolts *k*, to which the drift wires *c* are secured. The eye-bolts are passed through the slots *h* and receive on the inner side of the fitting *e* the nuts *m*, which are readily accessible through the open sides of the arch for the purpose of placing the drift wires under tension, without the use of turnbuckles.

Each fitting, as will be observed, is not only very light, but by reason of its shape is very stiff and holds the end of the strut securely in place besides affording a secure anchorage for the drift wires and permitting easy adjustment thereof.

I claim as my invention:

1. A fitting for a wing strut of an aeroplane, arched in a longitudinal direction, made concavo-convex transversely, provided centrally with an aperture to receive the end of the strut, and adapted to be secured to the wing-spar.

2. A fitting for a wing strut of an aeroplane, arched in a longitudinal direction, made concavo-convex transversely, provided centrally with an aperture to receive the end of the strut, and adapted to be secured to the wing-spar, the fitting being also provided with one or more slots for the attachment of one or more guy wires.

3. The combination in an aeroplane wing, of a wing-spar, a strut fitting secured to the wing-spar, arched longitudinally, concavo-convex in transverse section, and provided with a central aperture, and a strut seated in said central aperture and bearing against the wing-spar.

4. The combination in an aeroplane wing, of a wing-spar, a strut fitting secured to the wing-spar, arched longitudinally, concavo-convex in transverse section, and provided with a central aperture, a strut seated in the central aperture and bearing against the wing-spar, and guy wires secured to the fitting.

5. The combination in an aeroplane wing, of a wing-spar, a strut fitting secured to the wing-spar, arched longitudinally, concavo-convex in transverse section, and provided with a central aperture, a strut seated in the central aperture and bearing against the

2
wing-spar, and guy wires secured to the fitting, the fitting being provided with slots for connection with the guy wires.

6. The combination in an aeroplane wing,
5 of a wing-spar, a strut fitting secured to the wing-spar, arched longitudinally, concavo-convex in transverse section, and provided with a central aperture, a strut seated in the central aperture and bearing against the

wing-spar, and guy wires secured to the fitting, the fitting being provided with slots for connection with the guy wires, each of said guy wires having at its end an eye-bolt passed through the fitting and receiving a nut on the inner side thereof. 10

15 This specification signed this 24 day of September, 1917.

LEWIS G. YOUNG.
